UNITED STATES PATENT OFFICE.

MARY STARMER, OF NEWPORT NEWS, VIRGINIA.

GARMENT-SUPPORTER.

1,389,226.

Specification of Letters Patent.

Patented Aug. 30, 1921.

Application filed July 16, 1920. Serial No. 396,645.

To all whom it may concern:

Be it known that I, MARY STARMER, a citizen of the United States, residing at Newport News, in the county of Warwick and 5 State of Virginia, have invented certain new and useful Improvements in Garment-Supporters, of which the following is a specification.

My present invention relates to improvements in garment supporters adaptable for use by men or women and designed especially with the view of providing a device which will be comfortable, which will be efficient in performing its required functions, and 15 which withal is simple in construction and operation, durable, and inexpensive in cost of manufacture.

With the above and other objects in view, the invention consists in certain novel combinations and arrangements with a garment supporter of upper and lower fastening devices for attaching the device to a support and for attachment to a stocking for holding up the latter.

25 In the accompanying drawings I have illustrated one complete example of the physical embodiment of my invention, adapted for women's hose and constructed and arranged according to the best mode I have 30 so far devised for the practical application of the principles of my invention.

Figure 1 is a view in front perspective of a supporter embodying my invention.

Fig. 2 is a rear perspective view.

35 Fig. 3 is a detail view of the combined pin fastener and web attaching device at the top of the supporter.

Fig. 4 is a detail view of the pin fastener combined with the lower attaching buckle.

40 Fig. 5 is a detail view of the lower attaching buckle showing the ears for securing the pin fastener, before the ears are bent to locking position on the pin fastener.

Fig. 6 is a detail view of the upper buckle.

45 In the preferred form of my invention as illustrated in the drawings, I employ a web 1 which may be of elastic material similar in character to that usually employed in garters or suspending devices.

50 At the upper end of the web I provide a top buckle indicated as a whole by the numeral 2 and I also utilize a lower buckle indicated as a whole by the numeral 3. The upper buckle is designed for attachment to 55 the lower edge of a corset and the lower

buckle 3 is to be attached to the hose or stocking.

The attaching device 2 comprises a front plate 4 which may have any suitable ornamentation thereon, and is stamped from a blank or sheet of thin metal. The front plate is fastened with ends 5—5, and rear flanges 6—7, spaced back of the plate sufficiently to accommodate the pin fastening device which is indicated as a whole by the numeral 8 in Fig. 3. This pin fastening device has the resilient pin member 9 and coiled spring end 10, the former being passed through an opening 11 in the perforated ear 7 at the back of the plate 4. The pin member is provided with a pair of vertical bars 12—12 which are inclosed within the ears 13, 13 of the buckle 2, and by this arrangement the pin fastener is retained in the buckle member 2 and the pin 9 is snapped under the hook 14 of the pin fastener. It will readily be apparent that the pin 9 is designed to be passed through a supporting fabric, as for instance a portion of a corset, and the flanges 7 and 6 are utilized, the former as a support, and the latter as a guide for the pin 9. The flange 6 also forms a guard to prevent the point of the pin catching into any portion of the wearer's garments.

55 The base bar 15 of the pin fastener is provided with a pair of integral spurs 16 that penetrate the fabric of the web 1, which latter is passed around the bar 15, and stitched, as in Fig. 6, and by this means the top fastening device is secured to the web. 60

The lower buckle 3 is quite similar in construction to the upper buckle, and employs a front plate 17 slotted at 18 to accommodate the lower end of the web 1, which, is looped at 19 and passed upward through the buckle at the rear and then attached to the slide 18' on the web. 65

70 The front plate 17 has a guard flange 20 and a perforated supporting flange 21. The pin 22 is passed through the perforated ear 21 and its point is guarded by the flange 20. A coiled spring portion 23, is provided at one end of this pin fastener and a hook 24 is provided at the other end for the pin 22. Vertical bars 25 are also provided around 75 which the ears 26 are clamped to secure the pin fastener to the lower buckle.

78 The base bar 27 of the pin fastener has thereon a metal roller 28 provided with external studs 29 adapted to penetrate the ma- 80

aterial of the loop 19 to insure a stable frictional contact between the loop and pin fastener and to enable the loop to turn freely around the roller in adjusting the length of 5 the web 1.

The tassel 30 is attached at the front of the plate 17 by means of which the length of the suspending web may be adjusted through the medium of an adjusting buckle 10 18' on the web.

The pin 9 may readily be passed through the supporting fabric and engaged under its hook 14 which is guarded within the flange 6 and the coil 10 provides the requisite 15 resiliency for the pin.

Similarly the coil 23 provides resiliency for the pin 22 and the lower end of the garment supporter may be attached to the hose by this pin 22. The flange 20 serves 20 as a guard, and provides an additional keeper for the pin 22 as does the flange 6 serve as a guard and keeper for the pin 9.

The ears 13 and 26 as seen in Fig. 2 are adapted to be clamped around the bars 12 25 or 25 of the respective pin fastener, and these ears afford a stable support and connection between the pins and their plates.

Having thus fully described my invention, what I claim is—

30 1. The combination in a garment supporter with a web, of a pin fastening device including a pin member and approximately parallel bar, a plate having a rear perforated end flange and the pin member of said

fastening device passed therethrough, means 35 for securing the base bar at the ends of said plate, a hook for the pin member, and an end guard flange inclosing said hook.

2. The combination in a garment sup- 40 porter with a fastening device including a front plate having end walls and opposed rear flanges, one of which is perforated, of a pin fastening device having a pin member passed through said perforated flange, a base bar integral with said pin member, 45 means for securing the pin fastening device to said plate, and a hook on said device for said pin member.

3. The combination in a garment supporting device with an integral plate member 50 having end walls and rear flanges, one of which is perforated, of a fastening device comprising a pin member passed through said perforated flange and provided with a hook, end bars to said pin member, and end 55 ears on said plate clamped around said bars.

4. The combination in a garment sup- 60 porting device with a slotted plate member having spaced rear flanges one of which is perforated, of a fastener comprising a pin member passed through said perforated flange, a pin hook inclosed within the other flange, and bars on said fastener, and ears 65 on the front plate embracing said bars, a base bar, and a frictional roller on said base bar adapted to engage the loop of a web passed through said slotted plate.

MARY STARMER.
